UNITED STATES PATENT OFFICE

2,483,063

CARTON FORMING DEVICE

Don Ray, Beverly Hills, Calif., assignor to Arden Farms Co., Los Angeles, Calif., a corporation of Delaware

Original application March 27, 1939, Serial No. 264,376. Divided and this application December 21, 1942, Serial No. 469,770

6 Claims. (Cl. 93—51)

1

This invention relates to improvements in package making machines, and particularly pertains to a carton forming device, and is a division of my co-pending application entitled "Packaging," filed by me March 27, 1939, and bearing Serial No. 264,376, now Patent No. 2,307,076, issued January 5, 1943.

In the packaging of food products it is desirable in many instances to dispense the products in foldable carton containers within which the food may be held until used, and which containers are of a design and construction to permit them to be readily folded into position and held without the use of mechanical fastening means. It is also desirable to provide a carton with which a liner may be folded and assembled to insure that the product will not leak through the seams formed between the edges of the folded parts.

It is an object of the present invention to provide simple means whereby a carton may be formed from flat blanks, filled with a desired commodity and sealed.

It is an object of the present invention to provide means for folding and assembling a liner and carton blank in a single operation and by which means the outer carton will be folded and placed in a mold while associated with an inner liner which folds and interlocks with the carton elements to provide a receptacle for a product with which the carton is to be filled.

An object of this invention is to provide a mold adapted to receive and hold a folded container, said mold also guiding locking tangs of a cover into proper engagement with the container during a sealing operation.

A still further object is to provide a sealing device whereby flat cover blanks provided with locking tangs may be readily applied to a container.

The invention is illustrated by way of example in the accompanying drawings in which:

Fig. 1 is a perspective view of an octagonal package made in accordance with this invention.

Fig. 2 is a plan view of a pre-cut blank of a cover wrapper.

Fig. 3 is a plan view of an inner liner, one corner thereof being lifted to show the method of folding.

Fig. 4 is a plan view of a top lining.

Fig. 5 is a plan view of a top cover sheet.

Fig. 6 is a side elevation, diagrammatic in form, of a machine for forming the container or package.

Fig. 7 is a horizontal section taken along the plane 7—7 of Fig. 6.

2

Fig. 8 is a plan view taken along the plane 8—8 of Fig. 6.

Fig. 9 is an enlarged plan view of a portion of a package showing the manner in which it is formed.

Fig. 10 is a vertical section taken along the plane 10—10 of Fig. 9.

Fig. 11 is a side elevation, partly broken away, of a mold in which the container is formed.

Fig. 12 is a side view, partly in section, showing two positions assumed during the sealing of the container.

Fig. 13 is a diagrammatic side view of a forming, filling and sealing machine.

Fig. 14 is a plan view of a modified form of cover wrapper.

Fig. 15 is a vertical section of a forming mold containing the cover wrapper of Fig. 14.

Fig. 16 is a plan view of a modified liner.

Fig. 17 is a vertical section showing the position assumed by the liner in a forming mold.

Fig. 18 is a vertical section showing the position assumed by the liner and wrapper in the mold during filling.

Fig. 19 is a plan view showing the position of the container elements after the top liner is placed thereon.

Fig. 20 is a plan view showing the position after the stabilizing tangs are bent in.

Fig. 21 is a plan view of a top cover sheet.

Fig. 22 is a side elevation of a completed container using the elements of Figs. 14, 16 and 21.

Various products may be handled by the means and methods of this invention, such as, for example, butter, shortening, oleomargarine, ice cream, cheese, candy and various confections, dried or glazed fruit, salads, gelatins, etc., and the size and proportions of the container can vary somewhat with the bulkiness of the material which is being packaged for distribution. In the illustrative forms described hereafter and shown in the drawings, particular reference is made to a package which has been found particularly effective for use in distributing ice cream, cheese and the like.

By referring to Figs. 1 to 5, it will be noted that the container itself may be made from four elements, namely, a cover wrapper 1, a liner 2, a top liner 3 and a top cover 4. It is to be noted, also, that each of these elements is cut from a substantially flat and square sheet of suitable material so that there is very little waste of material and the largest possible number of wrappers, liners, etc., can be cut from a continuous sheet of material.

The cover wrapper 1 and the top cover 4 may be made from a heavier grade of paper, this paper being suitably lithographed or printed on its exterior and if desired coated with paraffin or other wax, a resinous thermoplastic or thermosetting material, etc. Water-resistant or waterproof coatings are desirable whenever the contents are of a character which may mold or which are semi-liquid or require placement of the container in refrigerators during storage. The inner liner 2 and the top liner 3 may be made of material lighter in weight; Pliofilm, which is a rubber-containing thermosetting product having waterproof characteristics, or any other suitable pachmentized, oil-treated, waxed or even untreated material can be used.

The cover wrapper 1 is substantially square, in flat form, and has a central field delineated by the score marks 10, 11, etc. This central field as shown is octagonal. Surrounding this octagonal field are side portions including the portions 12, 13, 14, etc. The corner portions 12, 14 and the like are provided with enlarged stabilizing tangs 15, 16, and the like. The members 13, 13' have short wings 18, 19 extending therefrom, the edges of said wings, such as the edges 20 and 21, being directed toward the score lines defining the octagonal field. The score lines 10, 11, and the like which define the field are of equal length and the members 12, 13, 14 and the like are therefore of equal width with the exception that the side members 13 and 13' have the wings 18 and 19 which extend from the parallel score lines 22, 23.

The side members 13 are also provided with a cutout portion 25 approximately triangular in form, the base of such triangular cutout portion being directed toward the field. The cut 26 extends from the base line of the triangular portion 25 toward the wings of the member 13.

Attention is also called to the fact that indentations or score lines 27, 28 and the like are formed in the stabilizing corner tangs, the fold indentations being parallel to the score lines 10 which delimit the field.

When a liner is used such as is shown in Fig. 3, such liner is also provided with an octagonal field defined by means of score lines 30, 31, etc. The field thus defined is preferably just a little smaller than the field of the cover wrapper 1. Perpendicular to these score lines 30 and 31 are other fold lines, such as 32, 33, 34, 35 and the like, defining side portions. A score line 36 also parallels the line 31 at a distance equivalent to the height of the final side wall of the container.

The edges 40 and 41 of the liner 2 are connected by means of the score line 36 so as to define a large octagonal field, the score line 36 being continued by a cut edge 42. Fold lines or score lines are also provided at 43, 44, 45, etc., these being directed to the points of intersection of the fold lines 30 and 31. The corner tang 46 is shown in a partially raised position so as to emphasize and disclose the manner in which the liner is folded along the various score lines during formation of a container.

The top liner 3, shown in Fig. 4, may be substantially square as shown and be provided with tab portions 50, 51, 52, which come into existence when the top liner 3 is folded along the score lines 53, 54, and the like. The top cover, shown in Fig. 4, is substantially square but the corners thereof are marked with the indented or scored lines 55, 56, and the like, said score lines together with the edges 57 and 58 defining an octagonal field. The locking tangs 59, 60 and 61 may be

provided with enlarged triangular heads having shoulder portions, such as 62 and 63. The total width of this locking tang at the shoulder portions should be substantially equivalent or very slightly smaller than the length of the cut line 26, exclusive of the base of the aperture 25 in the cover wrapper 1.

The elements described can be best combined to form a package by the use of a machine such as is shown in Figs. 6, 7 and 8. The cover wrapper 1, and if desired the liner 2, may be fed into the machine in superimposed relation immediately on top of a series of forming heads 70, 71, 72 and the like adjustably carried upon a stationary ring or frame 73. The forming heads are circularly arranged in spaced relation and in a horizontal plane. The various forming heads 70, 71, 72 are arranged with their axes at 90° to each other, the presser plates 70', 71' and 72' thus forming an incomplete square. Each of the forming heads may be adjustably mounted in the frame 73 and may be movable toward the center of such square along milled slots or guides in the frame 73, the heads being positionable by means of locking bolts such as 74. Each of the forming heads is provided with a presser plate which is mounted upon a stem 75 having an adjustment nut 76 and such plates are yieldably urged toward the center of the square by means of springs 77 (see Fig. 8). These presser plates are also provided with wings, such as the wings 78, 79, which are triangular in form, being broader and wider at the top and converging to a point at the bottom as best shown in Figs. 6 and 8. The total width 30 of the presser plates at the top (including the wings) should be approximately the same as the length of the edges 11 of the cover wrapper whereas the base of the presser plates 72' should be approximately equivalent to the width of the material 40 along the score line 11.

Immediately below the set of forming heads 70, 71, etc. is another series of forming heads 80, 81, and the like, these forming heads being also mounted for radial adjustment and being spaced from each other so as to work along lines bisecting the angles between adjacent upper forming heads. For example, the forming head 80 is positioned so as to operate along the line bisecting the line of movement of the upper forming heads 50 70 and 71. Adjustment means are indicated at 82. Each of the forming heads 80, 81 and the like is provided with a presser plate 80', 81' and the like mounted in a manner similar to that in which the upper forming plates are carried.

The faces of the various presser plates 70', 71', etc. should form a well approximately octagonal in cross-section and similar in size to the size of the field of the cover wrapper 1. An octagonal plunger 90 is provided of a size slightly smaller than the octagonal field of the cover wrapper and provided with means for reciprocally moving the plunger through the well formed by the various presser heads into a mold 91. Vertical bores 92 may be provided in the plunger 90 to provide means for releasing air. When the cover wrapper is made of a material capable of adhering or cohering to the liner or to itself in the presence of heat, the plunger 90 may be provided with heating elements 93, 94, 95, 96 and the like set into the vertical faces of said plunger for the purpose of supplying heat to desired areas of the cover wrapper and liner as such cover wrapper and/or liner is bent and folded by the downward movement of the plunger 90 through the 60 series of forming heads and into the mold 91.

The mold 91 is provided with an octagonal cavity 100 and an opening 101 in the bottom thereof. This mold is adapted to receive the cover wrapper and every other side of such octagonal mold is provided with means for securing the folded container within the mold while the plunger is withdrawn from the mold. Such means, for example, may comprise the spring-actuated pins or balls 102, such pins or balls being yieldably urged slightly into the octagonal cavity of the mold by means of a spring 103 contained in a cap 104. The pins or balls 102 constituting locking means are adapted to engage with the cutout portions 25 of the cover wrapper 4 (shown in Fig. 2). It will thus be evident that in operation the cover wrapper 4 is placed in position on the upper series of forming heads 70, 71, etc., and the downward movement of the plunger 90 carries the cover wrapper through the assembly of forming heads and into the mold 91, the cover wrapper being suitably folded and if desired cemented at its overlapping edges by the action of heat on the coating material of such wrapper.

The side pieces 13 and 13' are first bent inwardly by the forming heads 70 and 71 and the corner tangs 12 and 14 are then bent inwardly along the score lines 10 by the forming heads 80 and 81, this movement also causing the wings 18 and 19 to be bent inwardly, such wings being then covered by edge portions of the sides 12 and 14. In the event a liner 2 is formed at the same time, then the liner and the cover wrapper become interlocked as best shown in Figs. 9 and 10. Since the liner 2 is imperforate not only throughout the bottom field but also throughout the side portions, a substantially water-tight container may be made. In Fig. 9 the wing 19 is shown bent whereas the wing 18 has not as yet been bent by the upward movement of the corner tangs along the crease lines 10 and 31. The folded edge 45 of the liner is clearly shown in Fig. 10.

Fig. 11 shows the partially formed container including the cover sheet and liner within the mold 91. The molds 91 are then advanced in any suitable manner as, for example, by means of a conveyor, to a filling head generally indicated at 110 (Fig. 13) where such containers are filled while still in such molds 91. The conveyor 109 then moves the mold and its filled container to a sealing station, at which time a top liner may be applied and the top cover applied. Fig. 11 shows the top liner 3 applied to the filled container, the tabs 50 and 51 being folded down so as to cover the sides 13. The upstanding stabilizing tangs 15 and 16 are then folded down and a suitable sealing device applies the top cover 4.

As shown in Fig. 13, a stack of these top covers 4, indicated at 111, is fed into a sealing mold 112, said sealing mold being capable of rotation about a horizontal shaft 113 so that it can convey the top cover 4 into position immediately above the mold 91.

By reference to Fig. 12 it will be seen that the sealing mold 112 is hollow and contains a movable piston 113. The top cover 4 has been bent along its crease lines 55, 56, etc., so as to cause the locking tangs 59, 60, etc., to lie in vertical planes at right angles to each other. Downward movement of the piston 113 forces the locking tangs around the container in the mold 91, such locking tangs entering the slot 26 until the shoulders 62 and 63 of such locking tangs extend below the line of the cut 26. The plunger 113 is

then removed and the sealing mold 112 is retracted, leaving a completely filled and sealed container within the mold 91. The conveyor 109 then carries the mold to a discharge mechanism, not shown, whereby the filled and sealed containers are removed by the application of pressure to the bottom of the container through the port 101 in the bottom of the mold 91. In actual operation, from 15 to 25 containers of this character can be formed, filled with ice cream and sealed per minute.

The shoulders 115 and 116 of the locking tangs 15 and 16 cooperate with the top cover 4 and particularly with the inner surfaces of such top cover formed by bending the locking tangs along the crease lines 55 and 56 and thereby produce a finished container which is not readily deformable.

A modified form of cover wrapper, liner and top cover is shown in Figs. 14 to 22. The top cover sheet is indicated in Fig. 14 and it will be seen that it includes a center field, also octagonal in shape, delineated upon a flat square piece of material by the score marks 122. Corner tangs 123 are formed as a part of the cover wrapper and occur at the corners of the square blank. These tangs are defined by marginal edges 124 which delineate the blank and terminate in shoulders 125 disposed at right angles thereto, these shoulders extending inwardly toward each other until they intersect the cut edges 126 which emanate from and are at right angles to the score marks 122. Parallel to the score marks 122 and extending between the shoulders 125 are score marks 127.

The side folds 128 have an outer marginal edge in line with the edges 124 of the corner tangs. Score lines 130 are formed in these side members 128, thereby forming end flaps or wings 132. Cut into each of the rectangular center sections of the side folds 128 is a slit 133 parallel to the outer marginal edge and having small right angle slots 134 near the ends thereof. These slots are adapted to receive the locking tangs of the top of the container.

When the cover wrapper shown in Fig. 14 is folded into a forming mold, such as the mold 91 (see Fig. 15), the corner tangs 123 extend upwardly, whereas the wings 132 of adjacent side flaps 128 practically come in contact with each other.

Fig. 16 shows a modified form of liner provided with score lines 135 defining a central field of octagonal shape. This field is bounded by a marginal portion of uniform width whereby a larger octagonally shaped sheet is defined. This marginal portion comprises a plurality of rectangular fields 136 bounded on their inner sides by the score marks 135 and on their outer sides by an edge 137. Parallel score lines 138 at right angles to the score lines 135 form the rectangular side portions which eventually constitute sides of the container. Alternate fields 136 are provided with tangs 140, these tangs extending beyond score line 137. Score lines or indentations 139 connect the approximate points of intersection of the edges 137 and 137' with the score lines 135.

When such inner liner is formed in a forming mold, it assumes the position shown in Fig. 17. When the liner and cover wrapper are simultaneously folded, the various parts assume the position shown in Fig. 18 and the container thus formed can be filled.

Fig. 19 is a plan view of such container after

the tangs 140 have been bent inwardly and then covered by a top liner 141 similar to the liner shown in Fig. 4.

Fig. 20 shows the position assumed by the stabilizing tangs 123 after they have been bent in so as to cover the top liner 141.

Fig. 21 is a plan view of the top cover 142 and it is to be noted that said top cover is substantially square but has its corners marked with diagonally directed score lines 143, these score lines, together with the edges 144, delineating an octagonal field. The corner locking tangs 145 thus formed have marginal edges 146 disposed substantially at right angles and locking shoulders 147. The total width of these locking tangs between the shoulders should not exceed the length of the cut line 133 formed in the side flaps 128 of the cover wrapper.

This top cover 142 is applied in a manner similar to that previously described and the completed package is shown in Fig. 22. It is to be noted that the shoulders 147 of the locking tangs 145 cooperate with the edge formed by the cut line 133 so as to lock the top cover 142 in position.

It will thus be seen that the complete package is formed by the use of inexpensive flat sheets of suitable material and that the machine disclosed herein makes it possible for the blanks to be formed into a container, filled and sealed progressively in a minimum time. In the event the inner or outer surfaces of the outer wrapper are coated with a thermoplastic or thermosetting composition, then there is no necessity of employing locking tangs on the top cover and simply tabs insertable into slots cut in the side flaps of the bottom wrapper are sufficient since the application of heat to the overlapped areas of the bottom wrapper will cause the bottom wrapper to maintain its position with respect to the cover due to the action of the thermosetting coating.

The automatic continuous form of machine described herein permits the formed containers to be moved past a filling station and into operative relation with the sealing device. The packages can be removed from the container molds either manually or automatically. Obviously, the various motions, such as the downward motion of the plunger, the forward intermittent motion of the conveyor, and the intermittent action of the sealing mechanism including its ejector, are suitably mechanically interlocked and correlated; such correlation between the elements disclosed comes within the skill of the engineering arts and need not be described in detail herein. All changes, modifications and adaptations coming within the scope of the appended claims are embraced thereby.

It is to be understood that the machine disclosed herein may be used in the formation of containers provided with a liner or without a liner, depending upon the character and consistency of the commodity being packed. Although particular reference has been made to ice cream heretofore, glazed or dried fruits and other commodities may be handled in packages of the character disclosed herein.

I claim:

1. A machine for folding and depositing an imperforate container blank within a forming mold of polygonal shape, comprising a forming table having an opening therein, a plurality of forming heads arranged around said opening in spaced relation to each other in a common plane to agree with alternate side wall sections of the container, a plurality of additional forming heads to agree with intermediate side wall sections of

said container arranged around said opening in spaced relation to each other at a lower level than said first named forming heads, plunger means adapted to move downwardly through said opening to engage and carry said container blanks of sheet material through said opening and successively between forming heads at the two levels, whereby said blanks may be folded with a bottom and side wall sections and with gussets folded between and lying against the contiguous side wall sections to assume the configuration of the mold and to be deposited therein.

2. A machine for folding and depositing an imperforate container blank within a forming mold of polygonal shape, comprising a forming table having an opening therein, a plurality of forming heads arranged around said opening in spaced relation to each other in a common plane to agree with alternate side wall sections of the container, a plurality of additional forming heads to agree with the intermediate side wall sections of the container and arranged around said opening in spaced relation to each other in a common plane and at a lower level than said first named forming heads, said forming heads collectively agreeing in number and spacing with the side walls of a container to be formed, adjustable yielding forming shoes carried by a part at least of said forming heads, plunger means adapted to move downwardly through said table opening and to engage and carry the imperforate container blank of sheet material through said opening and successively between said forming heads at the two levels, whereby the side walls of the blank will be folded at right angles to the bottom of the blank and gussets occurring between contiguous side wall sections will be formed and folded against the faces of said sections preparatory to being positioned within said forming mold.

3. A machine for folding and depositing an imperforate container blank within a forming mold, said blank being a flat pre-cut sheet, including an octagonal body field and outwardly extending side wall fields adapted to be bent into planes at right angles to the plane of the body field with intervening gusset sections between the contiguous side wall fields, the machine comprising a set of forming heads circularly disposed in spaced relation in a common substantially horizontal plane to agree with alternate side wall sections, a plunger adapted to reciprocate between the forming heads, said plunger having a configuration to register with the octagonal field of the blank and to move the blank downwardly between said forming heads, whereby alternate side portions of said blank are folded, a second set of forming heads disposed in a lower horizontal plane and adapted to engage intermediate side portions of a blank passing therebetween to fold them upwardly with their intermediate gussets in overlapping relation to said alternate side portions of the blank to form a container and which formed container is then moved by the plunger into a forming mold.

4. A machine for forming polygonal shaped containers within a forming mold, which comprises a forming table having an opening therethrough and above which an imperforate flat sheet container blank is disposed, a plunger of polygonal shape agreeing with the configuration of the container to be formed and being normally disposed above said table and adapted to be moved downwardly through the opening therein and to carry said blank with it, a plurality of forming heads agreeing with alternate side

wall sections of the container and in a common plane disposed around said opening and over which the blank is placed, said forming heads registering with facets of said plunger and acting upon alternate side wings of the blank to fold the same upwardly as the plunger and blank move downwardly therebetween, a second set of forming heads disposed in a common plane beneath that of the first mentioned forming heads and acting upon the unfolded intermediate wings and to fold intermediate gusset sections against contiguous wings of the blank to fold said wings upwardly with relation to the first mentioned set of blank wings as the plunger continues its downward movement, during which time the plunger moves the blank into a forming mold.

5. A machine for forming containers by folding the same and placing them in a forming mold, which containers are formed from a blank comprising a polygonal body field bounded by a plurality of wings, one joined to each of the sides of said polygonal field and to each other along contiguous edges to provide a gusset section designed to overlap contiguous side wings when folded, which machine includes a forming table having a polygonal shaped opening therethrough agreeing with and through which the polygonal field of the blank may pass, a plunger of similar polygonal shape disposed above said forming table and adapted to reciprocate through said opening and to register with the polygonal field of the blank to move it downwardly, a set of forming heads disposed in a common upper plane and engaging alternate wings of the blank which must be first folded upwardly in forming the container, a set of forming heads in a second common plane adapted to engage intermediate wings of the blank as the plunger carries the blank downwardly between them and folds them upwardly with the gussets occurring between their contiguous marginal edges folded in overlapping relation to the first folded set of wings, whereby further downward movement of the plunger will place the folded blank within a forming mold.

6. A machine for forming containers from sheet material and depositing them in a forming mold, said containers being formed from an imperforate sheet container blank comprising a polygonal body field bounded by a plurality of separate wings forming side walls of the container and intermediate foldable gussets over-

lapping at contiguous edges of the wall wings when folded at right angles to the body field, and a liner having a polygonal body field corresponding to the polygonal body of the container blank and being formed with a plurality of interconnecting wall wings corresponding in number and shape with the wall wings of the body blank and having intermediate foldable gussets, which machine includes a forming table having a polygonal shaped opening therethrough substantially agreeing with the shape of the body field of the blanks, a plunger above said table corresponding in configuration with the body field adapted to reciprocate through said opening, a set of forming heads disposed in an upper common plane and above which the container blank and the liner blank are disposed in register, the liner blank being uppermost, said forming heads engaging alternate wings of the blank as the plunger moves downwardly, whereby one set of wings of the container blank and the liner blank will be folded upwardly, a second set of forming heads in a lower common plane adapted to engage the intermediate unfolded wings of the blank and to fold them upwardly and in overlapping relation to the contiguous edge portions of the first folded set of wings and simultaneously folding the liner within the container blank with the gusset portions folded into interengaging relation with the folded gussets at the edge of the wall wings of the blanks and folded there against, whereby the formed container may be carried downwardly by the plunger into a forming mold.

DON RAY.
